UNITED STATES PATENT OFFICE

MARTIN W. BRUESHABER, OF CHICAGO, ILLINOIS, ASSIGNOR TO THE GOSS PRINTING PRESS COMPANY, OF CHICAGO, ILLINOIS, A CORPORATION OF ILLINOIS

PRINTING PRESS

Application filed June 29, 1931. Serial No. 547,621.

The present invention relates to a new and improved rotary printing press and more particularly to a rotary printing press adapted for the high speed printing of newspapers.

Objects and advantages of the invention will be set forth in part hereinafter and in part will be obvious herefrom, or may be learned by practice with the invention, the same being realized and attained by means of the instrumentalities and combinations pointed out in the appended claims.

The invention consists in the novel parts, constructions, arrangements, combinations and improvements herein shown and described.

The accompanying drawings, referred to herein and constituting a part hereof, illustrate one embodiment of the invention, and together with the description, serve to explain the principles of the invention.

Of the drawings:—

Fig. 1 is an end view looking from one end of a rotary printing couple embodying the present invention, with certain parts broken away;

Fig. 2 is an end view looking from the other end of the mechanism shown in Fig. 1, with certain parts broken away;

Fig. 3 is a sectional view taken on the line 3—3 of Fig. 1.

In the usual practice of printing newspapers on high speed rotary presses, when running collect or cross-associate runs, the plate cylinders are considerably out of balance due to the difference in the weight of the several plates carried by the plate cylinders. This difference in weight and resulting lack of balance reduces the speed at which the cylinders may be satisfactorily operated and consequently holds down the maximum capacity of the press. While the condition referred to is particularly apparent at high speeds on collect and cross-associate runs, it generally exists under all operating conditions, resulting in vibration and wear which are eliminated or greatly reduced by the present invention.

The present invention has for its object the provision of a novel improved rotary printing

couple provided with means for reducing the vibration usually present when such couples are operated at high speeds. A further object is the provision of means for equalizing the torque on the plate cylinder shafts of rotary printing couples. Still another object is the provision of a novel means for increasing the quality of impressions and reducing wear on the parts of a rotary perfecting printing couple which is operated at high speeds.

In accordance with the present embodiment of the invention, the printing press comprises a rotary perfecting couple formed of a pair of impression cylinders cooperating with a pair of plate cylinders which are geared together in the usual manner and are rotatably journaled in end frames at the ends of the cylinders, and means are provided for reducing the out of balance condition of the plate cylinders due to the difference in weight between the printing plates carried by the plate cylinders. As embodied, the balancing means comprise fly-wheels securely fastened to the outer ends of the plate cylinder shafts, which fly wheels are dynamically balanced and increase the rotating mass of the cylinders and at the same time reduce the deflection of the relatively long and narrow cylinders. The increased mass not only tends to increase the evenness of running of the cylinders, but also increases the ratio between the unbalanced load and the rotating mass.

It will be understood that the foregoing general description and the following detailed description as well, are exemplary and explanatory of the invention, but are not restrictive thereof.

Referring now in detail to the present preferred and illustrative embodiment of the invention, as shown in the accompanying drawings, the rotary perfecting printing couple comprises a pair of relatively-long and narrow impression cylinders 10, 11 positioned between a pair of relatively long and narrow plate cylinders 12, 13. Plate cylinders 12 and 13 are provided with plate securing means 14 of conventional construction which securely hold the curved printing plates 14' on the surface of the plate cylinders

and the plate and impression cylinders are suitably journaled in the side frames 15, 16 of the press so that the plates carried by the plate cylinders 12 and 13 press the paper web 5 to be printed against the surface of the impression cylinders 10 and 11, respectively, in the usual manner.

Means are provided for driving the cylinders in proper timed relation at the same 10 peripheral speed and for this purpose the plate cylinder shafts 17, 18 are provided with gears 19, 20 which mesh with similar gears 21, 22 mounted on one end of impression cylinder shafts 23, 24, respectively. At the 15 other end of shafts 23, 24 are mounted intermeshing gears 25, 26, of which gear 25 meshes with the main driving gear 27 which is driven in turn by bevel gears 28 from the vertical driving shaft 29.

20 Suitable inking mechanism 30 is provided for each couple and is driven from the plate cylinders by gears 31, 32.

As illustratively embodied, the balancing means comprise relatively large fly wheels 25 33, one of which is securely fastened to each of the outer ends of the plate cylinder shafts 17 and 18 and are dynamically balanced with respect thereto so that they run without vibration at all press speeds. The fly wheels 30 are preferably substantial duplicates of each other and each comprises an annular portion 34 of relatively heavy mass connected with a hub portion 35 by means of a thin web 36. As embodied the mass of the annular portion 35 of the fly wheels is relatively large compared to the difference in weight of the plates 14', but is much smaller than the mass of the cylinders.

40 The fly wheels 33, being positioned at the ends of the shafts and externally of the side frames 15 and 16 between which the plate cylinders are supported tend to reduce the deflection of the central portion of the cylinders, thereby rendering the cylinders and 45 plates more true, increasing the uniformity of pressure between the plates and impression cylinders and rendering the cylinder more nearly dynamically balanced.

The invention in its broader aspects is not 50 limited to the specific mechanisms shown and described but departures may be made therefrom within the scope of the accompanying claims without departing from the principles of the invention and without sacrificing its chief advantages.

What I claim is:—

1. A rotary printing couple including in 60 combination a plate cylinder, an impression cylinder cooperating therewith, journals for said cylinders at the ends of the cylinders and fly wheels mounted coaxially with the plate cylinder one on the outer side of each plate cylinder journal and rigid with respect to the plate cylinder.

65 2. A rotary printing couple including in

combination a plate cylinder, an impression cylinder cooperating therewith, a pair of fly wheels rigidly fastened to the plate cylinder at its ends and spaced therefrom and journals for said plate cylinder between the fly wheels and cylinder. 70

3. A rotary printing couple including in combination a relatively long and narrow plate cylinder, a relatively long and narrow impression cylinder cooperating therewith, a pair of fly wheels rigidly fastened to the plate cylinder at its ends and spaced therefrom and journals for said plate cylinder between the fly wheels and cylinder. 75

4. A rotary printing couple including in combination a relatively long and narrow plate cylinder, a relatively long and narrow impression cylinder cooperating therewith, a pair of fly wheels rigidly fastened to the plate cylinder at its ends and journals for said plate cylinder between the fly wheels and cylinder. 80

5. A rotary perfecting printing couple including in combination a pair of impression cylinders, a pair of plate cylinders cooperating with the impression cylinders to form a rotary perfecting couple, said impression cylinders being positioned between the plate cylinders, pairs of fly wheels, one pair for each plate cylinder, side frames at the ends 90 of the cylinders in which the cylinders are journaled, intermeshing gears at one end of the impression cylinders, and intermeshing gears at the other end of the cylinders for gearing together each plate cylinder with 95 its impression cylinder. 100

6. A rotary perfecting printing couple including in combination a pair of relatively long and narrow impression cylinders, a pair of relatively long and narrow plate cylinders cooperating with the impression cylinders to form a rotary perfecting couple, said impression cylinders being positioned between the plate cylinders, pairs of fly wheels, one pair for each plate cylinder, side frames at the ends of the cylinders in which the cylinders are journaled, intermeshing gears at one end of the impression cylinders, and intermeshing gears at the other end of the cylinders for gearing together each plate cylinder with 115 its impression cylinder. 110

7. A rotary perfecting printing couple including in combination a pair of impression cylinders, a pair of plate cylinders to be plated for straight, cross-associate or collect runs and cooperating with the impression cylinders to form a rotary perfecting couple, said impression cylinders being positioned between the plate cylinders, pairs of fly wheels, one pair for each plate cylinder, side frames at the ends of the cylinders in which the cylinders are journaled, intermeshing gears at one end of the impression cylinders, and intermeshing gears at the other end of the cylinders for gearing to 120 125 130

gether each plate cylinder with its impression cylinder.

8. A rotary perfecting printing couple including in combination a pair of relatively long and narrow impression cylinders, a pair of relatively long and narrow plate cylinders to be plated for straight, cross-associate or collect runs and cooperating with the impression cylinders to form a rotary perfecting couple, said impression cylinders being positioned between the plate cylinders, pairs of fly wheels, one pair for each plate cylinder, side frames at the ends of the cylinders in which the cylinders are journalled, intermeshing gears at one end of the impression cylinders, and intermeshing gears at the other end of the cylinders for gearing together each plate cylinder with its impression cylinder.
10. A rotary perfecting printing couple including in combination a relatively long and narrow plate cylinder, a relatively long and narrow impression cylinder cooperating therewith, a pair of fly wheels rigidly fastened to the ends of the shaft of the plate cylinder and of larger diameter than the cylinder and journals between the fly wheels and the plate cylinder.
12. A rotary perfecting printing couple including in combination a plate cylinder and a cooperating impression cylinder geared together, means for securing a plurality of plates longitudinally and circumferentially of the plate cylinder, a pair of fly wheels rigidly fastened to the ends of the plate cylinder shaft and journals between the fly wheels and the plate cylinder.
14. A rotary printing couple including in combination a long and narrow plate cylinder, an impression cylinder cooperating therewith, a fly wheel rigidly fastened to the plate cylinder at one end and spaced therefrom and a journal for the plate cylinder between the fly wheel and cylinder.
16. A rotary printing couple including in combination, a plate cylinder, an impression cylinder cooperating therewith, and a fly wheel rotated by the plate cylinder and mounted near one end thereof.
18. A rotary printing couple including in combination, a plate cylinder, an impression cylinder cooperating therewith, and fly wheels rotated by the plate cylinder and mounted near the ends thereof.
20. In testimony whereof, I have signed my name to this specification.

MARTIN W. BRUESHABER.
